DESIGN FOR A CASING FOR A WATER COOLER

Lawrence L. Stone and Russell A. Mooney, Glendale, and Francis W. McFarlane, Maywood, and John G. McNiven, Los Angeles, Calif., assignors to Arrowhead and Puritas Waters Inc., Los Angeles, Calif., a corporation of California

Application August 31, 1940, Serial No. 94,759

Term of patent 14 years

To all whom it may concern:

Be it known that we, Lawrence L. Stone, Russell A. Mooney, Francis W. McFarlane, and John G. McNiven, all citizens of the United States of America, residing, respectively, in the cities of Glendale, Glendale, Maywood, and Los Angeles, all in the county of Los Angeles, State of California, have invented a new, original, and ornamental Design for a Casing for a Water Cooler, of which the following is a specification, reference being had to the accompanying drawing, forming part thereof.

Figure 1 is a front elevational view of a casing for a water cooler, showing our new design; Figure 2 is a side elevational view; Figure 3 is a bottom plan view; and Figure 4 is a rear perspective view, on a reduced scale.

We claim:

The ornamental design for a casing for a water cooler, as shown.
